WEIGHING SCALE

Robert M. Wolaver, Cleveland, Ohio, assignor to Toledo
Scale Corporation, Toledo, Ohio, a corporation of
Ohio

Filed Jan. 10, 1961, Ser. No. 63,495

Term of patent 14 years

(Cl. D52—10)

Fig. II

FIG. I is a front perspective view of a weighing scale showing my new design.

FIG. II is a rear perspective view of the weighing scale shown in FIG. I.

FIG. III is an enlarged, vertical sectional view taken along line III-III of FIG. I.

The undisclosed side of the weighing scale is substantially the same in appearance as the side shown. The characteristic features of my design for the scale disclosed reside in the transverse bar and transverse lever at the

upper part of the scale column having the configurations shown.

I claim:

The ornamental design for a weighing scale, as shown and described.
